HENRY J. LUCKE, OF NEW YORK, N. Y.

FILLING AND CHARGING DEVICE

Application filed February 6, 1930. Serial No. 426,204.

My invention relates to improvements in filling or charging devices; and particularly to a device for supplying combustible fluid to the interior of cigarette lighters and similar articles so as to keep them in readiness for constant use.

An object of the invention is to provide a charging device in which a supply of combustible fluid can be safely stored; and which is adapted for quickly charging a cigarette lighter without wasting the fluid or risk of accident.

A further object of the invention is to provide a filling and charging device that comprises relatively few parts and is easy to operate, and so constructed that the combustible fluid can be expelled from it and admitted to the inside of a cigarette lighter with a minimum of handling and in the quickest possible manner.

The nature of the invention is set forth in the following description and illustrated in the accompanying drawing which shows one embodiment for utilizing the invention in practice; but this disclosure is of course intended by way of example only, and I reserve the right to make changes in shape, size, arrangement of parts, and other details without going beyond the principle of the invention or exceeding the scope of the appended claims.

In the drawing, Fig. 1 is a vertical section through a filling and charging device according to this invention.

Fig. 2 is a detail view showing how the cigarette lighter is charged and filled; and

Fig. 3 is a section on line 3—3 of Fig. 1.

The same numerals identify the same parts throughout.

The numeral 1 indicates a vessel or reservoir having the form of a decanter or any other shape with a wide bottom to enable it to be placed upon a suitable supporting surface, in stable position, without risk of being easily upset. This reservoir may have a threaded opening to be closed by a screw plug 2, so that the contents may be replenished.

On the inside is a vertical cylinder 3, which is closed at its inner end and may rest on the bottom of the vessel 1. The opposite end

projects from the top of the vessel to a slight extent and is threaded on the exterior of the vessel, so that it can be closed by a screw-threaded perforated cap 4. The mouth of the vessel has an inward extending rim or flange 5 which encircles the cylinder 3 snugly, so that there can be no loss of the contents of the flask 1 by evaporation or leakage, and the cap 4 may rest upon this flange 5 if desired. Within the reservoir 1 is charged a quantity of gasoline or other suitable fluid.

The cylinder 3 is provided with one or more openings near its lower end, and one or more upper openings, these openings being indicated at 6. Within the cylinder is a piston 7, which is normally disposed between the upper and lower openings 6, and has a hollow stem 8 which is enveloped by a thicker hollow stem 9. Both the stems 8 and 9 pass through the cap or closure 4 and project above the top of the vessel 1; and the stem 9 is somewhat shorter than the stem 8, and at its upper end is expanded to form a bowl 10, just below the upper extremity of the stem 8.

The outer stem 9 terminates at its lower end at the top face of the piston 7 and is affixed thereto, while the stem 8 passes through the piston 7. Near the piston the stem 9 has one or more openings 11, which effects communication between the space inside the stem or conduit 9 and around the stem 8 with the interior of the cylinder 3. On the stem 9 within the cylinder and below the cap 4 is a fixed collar 13 and inside the cylinder 3 between the collar 13 and piston 7 is a fixed collar 14 having an opening through which the stem 9 can pass. A coiled spring 12 encircles stem 9 with its ends abutting the collars 13 and 14. This spring holds the piston 7 in partly raised position so that it will always be between the upper and lower openings 6.

To be filled by this charging device the cigarette lighter which is shown at 15, Fig. 2, is opened at the bottom by removing the plug screw which normally closes the threaded filling opening 16. The inside of the cigarette lighter has a wick of absorbent material 17, one end of which

projects through the top in the usual way and can be lit by means of a spark when the cigarette lighter is ignited. The bottom of the cigarette lighter is pressed against the rim of the bowl 10 with the protruding end of the inner stem 8 passing through the hole 16 to the inside of the cigarette lighter. The cigarette lighter is then forced downward depressing the piston 7. As the piston 7 passes downwardly toward and past the lower opening 6 gasoline is forced up through the stem 8 acting as a discharge nozzle to saturate the wick 17. When too much fluid is expelled from the stem 8 it flows back through the hole 16 into the returning means comprising the bowl 10, the stem 9 and holes 11 into the cylinder 3 and through the holes 6 into the flask 1. After the cigarette lighter is removed the hole 16 is closed by screwing in the plug for this hole and the expansion of the spring 12 again raises the piston 7 to starting position. The lower end of the cylinder 3 is always kept full of gasoline by flow through the lower openings 6, as soon as the pressure on the bowl 10 is removed so that the piston 7 can be raised again.

The device is thus very simple in construction and easy to operate. It is certain in action and involves no risk either of mishap nor waste of the fluid, because any excess fluid that is forced out of stem 8 can be intercepted and returned by the bowl 10 and stem 9, to the reservoir 1.

Whereas, I have described my invention by reference to specific forms thereof, it will be understood that many changes and modifications may be made without departing from the spirit of the invention.

I claim:—

40. 1. A filling device comprising a reservoir, a cylinder within the reservoir projecting from the top thereof and being closed at its bottom, said cylinder having openings spaced at different distances from said bottom, a piston in the cylinder and normally between said openings, a hollow stem connected to the piston and having openings therethrough adjacent to the piston, said stem projecting to the outside of the reservoir, a hollow stem within 45 the first stem passing through the piston and projecting from the reservoir beyond the end of the first stem, the outer end of the first stem being expanded to form a bowl surrounding the inner stem, so that pressure on the outer stem causes a portion of the contents of the reservoir to be expelled through the inner stem, any excess being caught by the bowl and returned through the outer stem to the inside of the reservoir.
50. 2. A charging device comprising a reservoir, a cylinder within the reservoir and projecting through the top, the inner end of said cylinder being closed, a perforated closure for the outer end of said cylinder, said cylinder having one or more upper and lower open-

ings adjacent its inner end, a piston normally disposed in the cylinder between the lower and upper openings, an outer hollow stem connection to the piston and projecting through the cap to the outside of the reservoir, said stem having openings adjacent the piston, the outer extremity of said stem being expanded to form a bowl, a collar on the inside of the cylinder, a collar on the stem inside of the cylinder, a spring encircling the outer stem between said collars, said spring acting normally to keep the piston between the upper and lower openings in the cylinder, and an inner stem secured to the piston and opening therethrough, the inner stem passing through the outer stem and protruding beyond the bowl thereof. 70 75 80 85

3. A filling device, comprising a reservoir, a cylinder, a piston disposed within said cylinder and cooperating therewith as a pump, a pipe member connected to the piston and communicating with the interior of said cylinder below said piston, and projecting from the cylinder to serve as a discharge nozzle, a second pipe member surrounding said first named pipe member and connected to said piston, said second named pipe member being provided with an opening communicating with the interior of said cylinder above said piston, said cylinder being provided with perforations disposed in two planes and communicating with the interior of said reservoir, one plane being located above the normal position of said piston within said cylinder and the other plane being located below the normal position of said piston within said cylinder, and resilient means tending to normally position said piston between said two planes. 90 95 100

4. A filling device, comprising a reservoir, a cylinder, a piston disposed within said cylinder and cooperating therewith as a pump, a pipe member connected to the piston and communicating with the interior of said cylinder below said piston, and projecting from the cylinder to serve as a discharge nozzle, a second pipe member surrounding said first named pipe member and connected to said piston, said second named pipe member being provided with an opening communicating with the interior of said cylinder above said piston, said cylinder being provided with perforations disposed in two planes and communicating with the interior of said reservoir, one plane being located above the normal position of said piston within said cylinder and the other plane being located below the normal position of said piston within said cylinder, and a spring having its one end fixedly positioned relative to said cylinder tending to normally position said piston between said two planes. 110 115 120 125

In testimony whereof I have signed this specification this 23rd day of January, 1980.

ARTHUR M. WICKWIRE, JR. 130
